U. S. PATENT OFFICE.

No. 76.

1861.

WHOLE No. 1,441.

Plates of a Parlor Stove.

JAMES HORTON AND JOHN MARTINO, OF PHILADELPHIA, PA.,

ASSIGNORS TO DAVID STEWART AND RICHARD PETERSON, OF SAME PLACE,

Letters Patent for a Design No. 76, dated July 16, 1861.

SPECIFICATION.

TO ALL WHOM IT MAY CONCERN:

Be it known, that we, JAMES HORTON and JOHN MARTINO, both of the city of Philadelphia, county of Philadelphia, State of Pennsylvania, have invented or produced a new and original design for the Plates of a Parlor Stove, termed the Patriot; and we do hereby declare the accompanying drawings, with the following explanation of the same, to form a full, clear, and exact description of the said design.

Fig. 1 of the drawing represents the bottom plate of the stove.

Fig. 2, the top plate; and

Fig. 3, the fire-door plate.

The top plate, fig. 1, of the stove, is of the form shown in the drawing, and has four ornamented mouldings, namely: the exterior moulding *a*; within the latter a second moulding *b*, which surrounds a third moulding *c*, within which is the fourth moulding *d*; the ornaments of the different mouldings, which are clearly represented, being different in character and design.

In the centre of the plate is an elevated and ornamented boss *e*, with openings, and in the rear of the plate is an elevated cap *f*, ornamented with ribs.

The bottom plate, fig. 2, is of the form shown, and has the four mouldings *h* *i* *j* and *k*, all being of the different designs clearly illustrated in the drawing.

The front of this plate has an ash-pit door *m* with a foliated ornament, and above the latter door is a smaller door *n* with a similar ornament.

Horton and Martino's Design for Plates of a Parlor Stove.

The fire-door plate, fig. 3, consists of two columns *p* and *q*, terminating below in ornamented bases, and above in ornamented capitals. The columns are connected together above by the ornamental cross-piece *t*, and below by an ornamental cross-piece *u*, the door itself having the openings *v v*, the edges of which are ornamented in the manner illustrated, the upper portion of the door having the word "Patriot" in raised letters.

We claim the combination of the ornamental figures and forms represented in and by the accompanying drawing, forming together an ornamental design for the plates of a parlor stove.

In testimony whereof, we have signed our names to this specification in the presence of two subscribing witnesses.

JAMES HORTON,
JOHN MARTINO.
